United States Patent Office.

CHARLES NELSON, OF NEW YORK, N. Y., ASSIGNOR TO HIMSELF AND
LOUIS KLUEBER, OF SAME PLACE.

Letters Patent No. 65,764, dated June 11, 1867.

IMPROVED TOY TORPEDO AND EXPLOSIVE COMPOUND.

The Schedule referred to in these Letters Patent and making part of the same.

TO ALL WHOM IT MAY CONCERN:

Be it known that I, CHARLES NELSON, of the city and county of New York, in the State of New York, have invented certain new and useful improvements in the Manufacture of Torpedoes for Children's Toys; and I do hereby declare that the following is a full and exact description thereof.

My torpedo is made of common and cheap materials, and involves the consumption of no paper or other valuable fibrous materials. The body is moulded in the proper form, with or without pressure, and the fulminate is introduced into a hole in the body, and the remainder of the hole is filled with the same or a different material from the body. The whole may be varnished and thus made impervious to moisture.

I will first describe what I consider the best means for carrying out my invention, and will afterwards designate the points which I regard as new therein.

The accompanying drawings form a part of this specification.

Figures 1, 2, and 3 represent sections, and Figure 4 is a view of my torpedo complete.

Figure 1 represents the clay body previous to the reception of the explosive material.

Figure 2 represents the same after the explosive material has been introduced.

Figure 3 shows the remainder of the hole filled up, and the whole varnished ready for transportation or use. Similar letters of reference indicate corresponding parts in all the figures wherever they occur.

A is a body, made of plastic clay. I prefer a mixture of about equal parts of fire-clay and pipe-clay; but the qualities of the clay may be very greatly varied without seriously modifying the effect of the invention. It is desirable that the composition shall be hard and strong enough to bear ordinary handling, while it shall at the same time be sufficiently soft and fragile to be shaken into small pieces by the action due to the explosion of the contents.

Other material than clay may be used, but I prefer the mixture as above described.

The material after being thoroughly kneaded with sufficient moisture to form a coherent mass, is pressed with more or less force, as may be found expedient, into a mould of proper form, which I do not consider it necessary to describe. The mould should fit together in two or more pieces, so as to make a mass either spherical or otherwise convenient and attractive; and the hole in the interior may be either of uniform size throughout, or slightly tapered. The latter form will more easily allow the withdrawal of the pin or former by which the hole is shaped. The body A is next thoroughly dried. I prefer to effect this in well-ventilated sheds protected from the direct action of the sun. After the drying, the composition described below, and which is indicated by B, is introduced in a pasty condition, and then the bolus or plug C is compressed upon the explosive composition, and when the whole is dried, the explosive material is enclosed at or near the centre of a nearly homogeneous mass of dry moulded material. After the whole has dried the surface is varnished, as indicated by D, and packed in saw-dust or otherwise for use or transportation.

The explosive material which I prefer and have used very successfully with my moulded bodies is compounded as follows: One-third amorphous phosphorus, one-third chlorate of potash, one-sixth sulphur, one-sixth pulverized chalk. These ingredients are compounded with sufficient water to form a paste, and may be introduced into the holes by hand or by machinery.

I have made my torpedoes for experimental purposes about half the size represented in the figures. I propose to make them larger or smaller as may be found desirable in practice. The torpedoes described, about one-half an inch in diameter, are harmless, and explode with a very loud report.

Having now fully described my invention, what I claim as new therein and desire to secure by Letters Patent is as follows:

1. I claim the toy torpedo herein described, having a body moulded in the form required, and composed of materials which shall be harmless in exploding, substantially as herein described.
2. I claim as an explosive composition for torpedoes and analogous uses the compound herein described, composed of materials in the proportions substantially as herein specified.

In testimony whereof I have hereunto set my hand in the presence of two subscribing witnesses.

CHARLES NELSON.
